CLAIM

The ornamental design for a film storage container, as shown and described.

DESCRIPTION

FIG. 1 is a generally perspective view of a film storage container showing my new design;

FIG. 2 is a right side view thereof;

FIG. 3 is a top view thereof;

FIG. 4 is a front view;

FIG. 5 is a rear view thereof;

FIG. 6 is a left side view; and,

FIG. 7 is a bottom view, the broken lines showing a like unit attached being for illustrative purposes only and forming no part of the claimed design.

FIG. 1

FIG. 2

FIG. 3

FIG. 4

FIG. 5

FIG. 6

FIG. 7
